UNITED STATES PATENT OFFICE.

JAMES B. POOLEY, OF PHILADELPHIA, PENNSYLVANIA.

DESK.

SPECIFICATION forming part of Letters Patent No. 360,473, dated April 5, 1887.

Application filed February 11, 1887. Serial No. 227,917. (No model.)

To all whom it may concern:

Be it known that I, JAMES B. POOLEY, of the city and county of Philadelphia, in the State of Pennsylvania, have invented a certain 5 new and Improved Device for Automatically Operating the Slides or Rests of Desks, &c., of which the following is a specification.

The object of my invention is to provide a device of simple construction, and at the same 10 time durable, for operating automatically the slides or rests of desks and other articles of furniture, and which, for example, in its application to desks is called into action both by the lowering and raising of the lid or "fall" 15 thereof.

The nature of my invention will be more 20 fully understood by reference to the accompanying drawings, forming part hereof, where- in I have shown my improved device in its application to a desk or secretary in a form 25 found practically efficient, and in which—

Figure 1 is a perspective view of a desk 25 broken away to show one of the slides pro- vided in the respective ends thereof for sup- porting the lid when lowered, and with the automatically-operating device applied thereto. Fig. 2 is a cross-section of a desk with the lid closed, showing my improved device for 30 operating the slides supporting the lid when lowered, and attached, respectively, to the lid and slides, and also showing in dotted lines the extended position of one of the slides when the lid is lowered ready for immediate use. Fig. 3 is a perspective view of one part of the 35 device, showing the rectangular bar hinged to and fitting snugly into a metallic T-shaped channel suitably fitted into the desk-lid; and Fig. 4 is a similar view, partly in section, showing the inverted-T-shaped rail rigidly se- 40 cured to one of the slides and traveling through the T-shaped channel-bar suitably fitted to place in the frame-work of the desk at each end thereof.

Referring to the drawings for a further de- 45 scription of my invention, A represents any ordi- nary well-known construction of secretary or desk provided with legs a and a', base b, and end b'. The front extremities of the re- 50 spective ends are preferably made so as to slant from the top of the desk, b', to the base b. Suit- ably hinged to the base is a lid, c, of any de- sired construction. In this base b, near the

ends b' and b'', respectively, are provided ob- long channels d, extending to the back of the desk, into which are inserted slides e, made of 55 wood or any other suitable material, having upward-projecting extremities f, to which in- 60 vited-T-shaped rails g are rigidly secured by screws or any other suitable means.

Above the channels d, and in the same hori- 60 zontal planes with the projections f of the slides e, are fitted rigidly to the frame-work b of the desk A T-shaped channeled bars h, made of any suitable metal, and through which the inverted-T-shaped rails g are permitted to 65 freely travel backward and forward by the 70 raising and lowering of the lid c of the desk A.

The inverted-T-shaped rails g are respect- 70 ively bifurcated at one of their extremities, and to their bifurcated ends are hinged, by means of rivets g', rectangular bars i, hinged to channeled bars h by means of pins or rivets l. The channeled bars h are respectively fitted into the lid c, so as to be flush with the inside 75 face of the same, and into which channeled bars fit snugly the rectangular bars i. The combined arrangement of the parts hereinbefore fully described furnish not only additional support to the lid c, constituting the table of 80 the desk when lowered, but, moreover, effect- ually prevent the breaking of the hinges of the lid c when lowered, because the slides e are 85 automatically operated therewith by the low- 90 ering and raising of the same, as will be fully ap- preciated without further description thereof.

While I have described my invention with 95 special reference to its application to desks, yet nevertheless it is obvious that there are other uses to which it may be successfully ap- plied in other classes of furniture; and hence I do not wish to be understood as limiting myself to its use in desks.

I am aware that a desk has been provided with slides having friction-rollers journaled thereto and with connecting-rods pivoted to 95 said slides and to the leaf of the desk, and hence I disclaim such form of a desk.

Having thus described the nature and ob- jects of my invention, what I claim as new, and desire to secure by Letters Patent, is— 100

1. A device for automatically operating the slides or rests of desks, consisting of one or more rails secured to slides or rests and play- ing freely within channeled bars set into a

desk, and with rectangular bars hinged to said rails and to other channel-bars set into the lid of a desk, substantially as and for the purposes set forth.

- 5 2. A device for automatically operating the slides of desks, consisting of two T-rails rigidly secured to slides having projecting end extremities, said rails playing freely through T-shaped channel-bars set into a desk, and 10 with rectangular bars hinged to said T-rails and to channel-bars fitted into the lid or fall of the desk, substantially as and for the purposes set forth.
3. A desk having two slides or rests and a

hinged lid, in combination with two rails playing freely through channel-bars fitting into said desk, and with rectangular bars hinged to said rails and to channel-bars set into the lid of the desk, substantially as and for the purposes set forth.

In witness whereof I have hereunto set my hand in the presence of two subscribing witnesses.

JAMES B. POOLEY.
